ROLLING EYES FOR DOLLS

Filed Feb. 1, 1926

UNITED STATES PATENT OFFICE.

ALEXANDER KONOFF, OF NEW YORK, N. Y., ASSIGNOR TO MARKON MANUFACTURING CO. INC., OF NEW YORK, N. Y., A CORPORATION OF NEW YORK.

ROLLING EYES FOR DOLLS.

Application filed February 1, 1926. Serial No. 85,153.

This invention relates to an improvement in doll's eyes, and particularly in doll's eyes which have a rolling movement as well as an opening and closing movement, such eyes being commonly known in the trade as rolling eyes.

An object of the present invention is to provide a pair of eyes which are simple and inexpensive in construction, which may be easily connected with their supporting rod, and which when in use will be capable of performing all of the movements customarily found in so-called rolling eyes.

A further and more detailed object is to provide an improved and simplified means for connecting the eye shells with their supporting and operating parts, to the end that they may be not only easily assembled but also be capable of adjustment in various ways to enable the proper functioning of the eyes in the doll's head.

A further object is to so construct the eyes that they each comprise a separate and distinct entity capable of being manufactured as such preparatory to being assembled and connected for uniform operation.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawings which are to be taken as a part of this specification, and in which I have shown merely a preferred form of embodiment of the invention:—

40 Fig. 1 is a rear elevational view of an eye set constructed in accordance with this invention.

Fig. 2 is a rear view of one of the eye shells, the control piece being omitted.

45 Fig. 3 is a horizontal sectional view, partly in elevation, upon the plane of line III—III of Fig. 1.

Fig. 4 is a vertical sectional view taken substantially upon the plane of line IV—IV 50 of Fig. 1, and

Fig. 5 is a side elevational view, on a reduced scale, of a modified construction in which the eye shell and its control piece are formed from an integral piece of material.

Referring to the drawings for describing in detail the structure shown therein, the reference character L indicates the usual bracket member by means of which the eye set is intended to be connected with the inner surface of the forehead portion of a doll in any well known manner.

The reference character G indicates the cross, or supporting, rod, which is rotatably mounted at the lower end of the bracket plate and which carries at its opposite ends the two eyes H—H.

The rod G has fixed thereto a pendant arm 1 at its central portion said arm being suitably bent and formed so that its end portion as 2 is adapted to abut against an inner surface as 3 of the doll's head 4 at a proper point to limit rotary movement of the rod G in one direction. This arm is constructed so that it may be bent by a workman when and as required to alter the exact limit of rotation of the rod G.

The rod G has also fixed thereto a second, and shorter, arm 5, preferably provided as an extension of the same piece of material as constitutes the arm 1. The arm 5 moves within a slot 6 provided in the bracket plate L and is adapted to engage against the upper end wall 7 of said slot to limit rotary movement of the rod in the direction opposite to the direction limited by the arm 1. The presence of the arm 5 within the slot 6 also serves to hold the rod G against excessive longitudinal movement in the bearings 8 provided upon the bracket plate.

The eyes H—H are identical in construction and operation, except that they are made rights and lefts, and a description of one will apply to both, as follows:

The hemispherical shell 9 has a notch 10 in one side thereof through which projects the supporting rod G.

The attaching member 11 is arranged at the rear of the shell 9 and consists of what will be termed a main flat plate portion 12, and a stem portion 13. The main plate portion 12

extends vertically across the rear side of the shell 9 and has pivotal extension parts 14—14 provided at its opposite ends extending through bearing apertures 15 provided to 5 receive them in the shell.

The stem portion 13 of the attaching member projects laterally from the main plate portion 12 and consists of a tubular sleeve adapted to telescope over the end of the supporting rod, the plate portion being preferably formed with a groove 16 therein so as to provide unobstructed longitudinal movement of the sleeve along the supporting rod. 10

The stem or sleeve 13 is formed from sheet metal bent into tubular shape but the edges are preferably not fixedly connected together. 15 These edges may or may not have engagement with each other as suggested in my pending application Serial No. 18,627. The sleeve is normally of less internal diameter than the external diameter of the supporting rod and must therefore be expanded when being forced onto the rod. Sufficient friction is thus generated to retain the sleeve in any position to which it is adjusted either longitudinally or rotatably upon the rod. 20

The plate portion 12 is preferably formed as an integral part of the same piece of sheet metal comprising the stem 13 and these parts 30 are so formed, and the bearing apertures 15 are so positioned, that said bearing apertures stand substantially in a common vertical plane with the centre of the supporting rod and the spherical centre of the shell in order 35 that no appreciable bodily displacement of the shell will accompany rotary movement of the shell when the shell swings about the vertical axis provided by the pivot parts 14 and 15 or when the attaching member is being 40 rotatably adjusted about the supporting rod incident to bringing the shell into a properly adjusted position with respect to the eye openings of a doll's head.

Longitudinal movement of the attaching member 11 along the supporting rod will of course correspondingly move the eye shell along said rod. 45

It will be understood that since both eye shells are connected with the same supporting rod, both of said shells will rotate in unison during all opening and closing movements of the eyes. 50

Fixed to the rear of the eye shell is a member 16^a which for convenience is here referred to as a control piece. This member or piece may be connected with the shell in any approved or satisfactory manner and has a tail portion 17 extending away from the shell carrying a weight 18. The tail 17 is extended 55 downwardly from the shell and the weight 18 is arranged adjacent its lower end, from which it will be seen that by moving the doll from an upright to a reclining position the weight will swing from its normal position 60 as in Fig. 4 backwardly by gravity and thus

cause the eye to move from its open to its closed position, as will be readily appreciated by those skilled in this art.

In its normal position, as seen in Fig. 4, the weight is held by the arm 1 against swinging downwardly to a position directly vertically beneath the supporting rod G since in this way the weight will serve more efficiently to hold the eye steadily in an open position during the handling of the doll in an upright position. Also the arm 1, by always impinging against the same point, as 3, of the doll's head will insure against contact of the tail 17 with any other part of the doll's head especially during the side-wise swinging of 75 said tail, as will now be referred to. 80

The arm 1, by always holding the weight 18 at a point at one side, that is rearwardly, of the vertical plane of the supporting rod, and hence rearwardly of the axial line of the 85 pivots 14, also enables the weight to perform the added function of a gravity member for causing the shell to rotate or roll about the pivots 14 whenever the doll is inclined to the right or the left whether the doll be in a fully 90 upright position or otherwise.

The control piece 16^a is formed with a narrow neck 19, or other suitable means by which it may be readily bent by a workman in order to dispose the weight at the most 95 suitable and advantageous position with respect to the eye shell and the arm 1.

The means illustrated in the drawings for holding the control piece fixed to the eye shell consists in forming the control piece 100 with a plate portion 20 which extends across the rear side of the shell in surface contact against the upper and lower rear edge portions of the shell as at 21 and 22, and of providing a plurality of tangs as 23 projecting 105 rearwardly from the shell and bent over adjacent portions of the plate 20 so as to hold the plate pressed firmly and immovably against the edge of the eye shell.

The central portion of the plate 20 is 110 bulged backwardly as at 24 so as to accommodate the attaching member 11 and enable the shell to rotate upon the pivots 14.

An edge corner as 25 of the bulge 24, see 115 Fig. 3, will serve as a stop to engage the stem of the attaching member for limiting rotary movement of the shell about the pivots 14 in one direction and the bottom wall as 26 of the notch 10 in the shell will engage against the stem to limit rotary movement of the 120 shell in the opposite direction.

Since both eyes are constructed in the same way and each are with an operating weight it follows that when they are in position on the supporting rod G they are properly balanced with respect to the bracket L and also that any lateral tilting of the doll sufficient to cause a rolling movement of one eye will cause a corresponding rolling movement of the other eye. In order however to insure 125 130

- against any possible differences in extent or time of the rolling movement of one eye with respect to the other it is preferable that they be connected together and for this purpose
- 5 the drawing herewith illustrates the presence of a connecting link as 27 which has its opposite ends pivotally connected as at 28 and 29 with the lower end portions of the two control pieces 16^a. The pivotal connections
- 10 at 28 and 29 are sufficiently loose to permit of all necessary adjustments of the tail parts of the control pieces, or the eyes rotatably or longitudinally along the supporting rod, as well as to permit of unobstructed swinging
- 15 of the control pieces at all times. The connecting link is preferably made adjustable in length, as by being formed with a V-shaped bend 27, since by this means the two eyes may be brought to their proper relative
- 20 positions rotatively of the pivots 14 following adjustments toward or away from each other longitudinally along the rod G.

It should be noted that while the attaching member 11, and particularly the plate portion 12 thereof carrying the pivot extensions 14, is normally in a somewhat inclined position with respect to the true vertical, thus rendering the weight 18 more efficient in effecting rolling of the eyes when the doll

25 is in an upright position, see Fig. 4, yet said attaching member and its pivots 14 will be, for convenience of description here, understood as providing rotation of the eye shell about a substantially vertical axis as compared with the substantially horizontal axis

30 of the supporting rod G. In this way the two distinct movements of the shell may be better understood and appreciated.

In the modification seen in Fig. 5 the construction and operation is identical with what has already been described except that in this figure is illustrated an arrangement by which the eye shell and the control piece are formed as a single integral member, preferably of stamped sheet metal, instead of the two separate pieces held together by the tangs as above set forth.

As many changes could be made in this construction without departing from the scope of the invention as defined in the following claims, it is intended that all matter contained in the above description or shown in the accompanying drawings shall be interpreted as illustrative only and not in a limiting sense.

Having thus described my invention, what I claim as new and desire to secure by Letters Patent is:—

1. An eye structure comprising a semi-spherical eye shell, a supporting rod therefor, an attaching member by which to connect the eye shell with the supporting rod, said attaching member comprising a portion providing pivots by which the eye shell is rotatable on
- 60 a vertical axis, the attaching member also

comprising a stem portion having slidable and rotatable adjustable connection with the supporting rod, and a weight connected with the eye shell operable to rotate the shell by gravity about said vertical axis.

70

2. An eye structure comprising a semi-spherical eye shell, a supporting rod therefor, an attaching member by which to connect the eye shell with the supporting rod, said attaching member comprising a portion providing pivots by which the eye shell is rotatable on a vertical axis, the attaching member also comprising a stem portion having slidable and rotatable adjustable connection with the supporting rod, and a weight connected with the eye shell operable to rotate the shell by gravity about said vertical axis, together with means whereby the weight is adjustable with respect to the eye shell.

80

3. An eye structure comprising a semi-spherical eye shell, a supporting rod therefor, an attaching member by which to connect the eye shell with the supporting rod, said attaching member comprising a portion providing pivots by which the eye shell is rotatable on a vertical axis, the attaching member also comprising a stem portion having slidable and rotatable adjustable connection with the supporting rod, a tail piece provided upon the eye shell having a weight at the lower end thereof operable to rotate the shell by gravity about said vertical axis, and said tail piece being bendable to thereby adjust said weight with respect to the eye shell.

90

4. An eye structure comprising a semi-spherical eye shell, a supporting rod, means by which the eye shell is connected with the supporting rod providing rotary movement of the shell about an axis transverse to the length of the rod, a member fixed to the shell and extending therefrom carrying a weight by which the shell is gravity controlled to swing about said axis, a part of the shell providing a stop to engage the supporting rod for limiting rotary movement of the shell in one direction, and a part of said mentioned member providing a stop to limit rotary movement of the shell in the opposite direction.

100

5. An eye structure comprising a semi-spherical eye shell, a supporting rod, means by which the eye shell is connected with the supporting rod providing rotary movement of the shell about an axis transverse to the length of the rod, gravity actuating means to actuate said shell, and means provided upon said shell co-acting therewith to define an opening through which the rod extends, opposite wall parts of said opening constituting stops to limit movement of the shell in opposite directions about said axis.

115

In testimony whereof I affix my signature.

ALEXANDER KONOFF.
